CHILDREN'S THEATER

William W. Collinger, Maynard C. Rosen, William E. Hunn, and Eugene Levin, all of St. Louis, Mo.

Application July 10, 1959, Serial No. 56,720

Term of patent 7 years

(Cl. D34—15)

FIG. 1

FIG. 2

Figure 1 is a perspective view of a children's theater showing our design, the opposite side being substantially a mirror image thereof.

Figure 2 is a top plan view thereof.

The characteristic feature of our design resides in the portion shown in full lines.

We claim:

The ornamental design for a children's theater, substantially as shown and described.
